UNITED STATES PATENT OFFICE.

MICHAEL G. DELANEY, OF DETROIT, MICHIGAN, ASSIGNOR, BY MESNE ASSIGNMENTS,
TO NORTHERN SALES CO., OF TOLEDO, OHIO, A CORPORATION OF OHIO.

REGULATOR FOR FILM-MACHINES.

1,144,694.

Specification of Letters Patent. Patented June 29, 1915.

Application filed September 22, 1913. Serial No. 791,157.

To all whom it may concern:

Be it known that I, MICHAEL G. DELANEY, a citizen of the United States of America, residing at Detroit, in the county of Wayne and State of Michigan, have invented certain new and useful Improvements in Regulators for Film-Machines, of which the following is a specification, reference being had therein to the accompanying drawings.

- 10 In the operation of machines for projecting pictures from films such as are in common use for moving picture exhibits, it is desirable, in order that a clear projection of the picture may be made that the film be held in fixed relation to the lantern lens. This is provided for in a manner by passing the film wound from the reel or container over suitable guiding mechanism but if the container from which the film is drawn is retarded, the film is likely to be injured by the undue strain.

This invention relates to regulating means whereby an even tension is maintained in the film as it passes from the magazine or container through the projecting machine, receiving roll or other container whereby strain on the film as it crosses the lantern or slide opening is prevented.

The invention consists in the matters hereinafter set forth and more particularly pointed out in the appended claims.

In the drawings, Figure 1 is a view in front elevation of one form of magazine or reel holder fitted with a device that embodies features of the invention; Fig. 2 is a view in rear elevation, showing electrical connections in diagram of a clutch circuit of the magazine or container; Fig. 3 is a view, partially in section and partially in side elevation, of the magazine or container, a projecting machine and the governing means, and Fig. 4 is a view in detail of an independent motor drive.

Referring to the drawings, a reel 1 of any preferred type, that is herein shown as adapted to deliver from the interior turns of a coiled film 2, is so mounted in a suitable casing 3 that the film is drawn therefrom through a delivery opening indicated at 4 and passes downwardly through a slot shown at 5 in the casing through a pro-

jecting machine having suitable mechanism of the usual type indicated at 6. The latter includes spur wheels 7 and 8 operated through suitable reduction mechanism 55 whereby the film which has the usual apertures 9 for positively engaging the spur wheels, is passed through guide members indicated at 10 which maintain it in the proper relation to a lantern or other like 60 illuminating and projecting device (not shown). The mechanism may be operated manually as herein indicated through the medium of a crank handle 11. In the normal condition of the apparatus and its normal operation, rotation of the crank handle draws the film from the reel or container 1 downwardly through the guides and guide rolls, the reel 1 delivering the ribbon as 65 needed. If for any reason, the film is frictionally retarded, a controlling roller 12 that is normally held by a tension spring 13 against the film is moved backward by the strain on the film as the latter tightens so that a stem 14 of a yoke on which the roll 12 70 is mounted, moves a connecting bridge piece 15 or the like between a pair of spring fingers 16 or other terminals. The latter are in series through a suitable electric circuit indicated diagrammatically at 17 with an 75 electric battery or other generator therein. The electric circuit also includes the field coils 18 of a magnetically thrown clutch. One member 19 of the clutch is connected to a sprocket wheel 20 or the like that is rotatable on a shaft 21 that operates the reel 1 if necessary. The other member 22 of the clutch that is keyed to the shaft 21 is arranged to frictionally engage with the member 20 when drawn against the latter by the 80 action of the excited field coils 18. The sprocket wheel 20 of the clutch is connected as by a chain 25, beveled gear train 26 and sprocket and chain connections 27 with the shaft turned by the crank handle 11 so that 85 when the clutch is thrown in the reel 1 revolves in positive relation to the projecting mechanism and thereby relieves the strain on the film. When the film slackens, the connecting bridge 15 is moved out by the 90 spring 13, and the clutch thereby released.

In Fig. 4, the clutch 22 with the tension

roller 12, terminals 15 and 16, and bridge piece 14, is shown as operating to couple a carrier shaft 28 to a motor 29 that is mounted on a bracket 30 or other convenient support whereby the carrier is rotated independently of the film projecting machine, whenever the film becomes too taut.

As a result of this construction any retardation of the film above the normal as it passes out of the magazine or container, shifts the governing roll and thereby closes the electric circuit. This automatically throws the clutch into engagement and causes positive rotation of the film reel or containing magazine and the reel projecting mechanism on which the film is being wound. This prevents any undue strain of and injury to the film. The device does not add materially to the complexity of mechanism and is effective to produce the desired result.

Obviously, changes in the details of construction may be made without departing from the spirit of my invention and I do not care to limit myself to any particular form or arrangement of parts.

What I claim is:—

1. The combination with a film holder and a projecting machine adapted to draw a film therefrom, of normally disconnected mechanism for positively discharging a film from the holder, and means adapted to be controlled by a film passing to the machine for connecting the mechanism when the tension of the film is abnormal.

2. The combination with a film holder and a projecting machine, adapted to draw a picture film from the holder, of means for rotating the holder, and means for connecting the rotating means to the holder controlled by the tension of a film passing from the holder.

3. The combination with a film holder, and guiding mechanism for a film passing therefrom, and means for passing a film through the guiding means from the holder, of means for positively turning the holder, means for coupling the holder to the turning means, and means controlled by the tension of a film passing over the guiding mechanism for throwing in the coupling means when the tension of a film engaged by the guiding means varies from normal.

4. The combination with a film holder and guiding mechanism for a film passing therefrom, and means for passing the film through the guiding means from the holder, of normally disconnected mechanism controlled by the tension of a film passing over the guiding means and adapted when thrown in by abnormal tension of the film to turn the holder, and to release the holder to turn independently when the film is under normal tension.

5. The combination with a film magazine,

of a film projecting machine, adapted to draw a film therefrom, means for regulating the delivery of the film from the magazine that is normally inert, and means controlled by the tension of a film passing from the magazine to the machine for throwing the regulating means into operation.

6. The combination with a casing, a film carrier rotatably mounted therein, mechanism for positively turning the carrier, a projecting machine adapted to draw a film from the carrier through an outlet in the casing, and means for coupling the driving mechanism of the carrier with the operating mechanism of the machine, controlled by a film passing over the guiding means.

7. A regulator for film machines, comprising a casing, mechanism for positively turning a film carrier in the casing, a projecting machine for positively drawing a film from the casing, and means adapted to be controlled by such film and arranged to connect the projecting machine and carrier turning means to move together.

8. A regulator for a film machine comprising a casing, a rotatable shaft on the casing for receiving a film carrier, means for rotating the shaft, a clutch for coupling the rotating means to the shaft, a projecting machine adapted to draw a film from the casing, and clutch controlling means governed by the tension of the film drawn from the casing by the machine.

9. The combination with a casing having an outlet opening, a film carrier shaft rotatable therein, a carrier mounted on the shaft, a projecting machine adapted to draw a film from the outlet opening, a regulator moving transversely to the path of a film drawn from the outlet, a clutch controlled by the regulator and adapted to engage the shaft when the regulator is moved by the tension of a film, and shaft rotating means adapted to be coupled to the shaft by the clutch.

10. The combination of a film carrier, a projecting machine adapted to draw a film from the holder, and mechanism for positively operating the carrier that is normally disconnected from the projecting machine, of a spring projected regulating member adapted to bear against a film passing through the machine, and a clutch for engaging the carrier operating mechanism with the machine that is thrown in by the regulator when the film moves the regulator to a predetermined point.

11. In a film winding machine, a casing having a delivery outlet, a shaft rotatable therein, a film reel adapted to be secured to the shaft, a regulating roll, tension means for yieldingly projecting the roll against a film drawn from the outlet, a projecting machine for guiding a film from the outlet, mechanism for positively turning the guiding means, a clutch adapted to couple the

turning means to the casing shaft, electrically energized means for throwing the clutch in including an electric circuit, and a make-and-break mechanism controlled by

5 the roll and adapted to close the circuit to throw the latter in.

In testimony whereof I affix my signature in presence of two witnesses.

MICHAEL G. DELANEY.
